[57] CLAIM

The ornamental design for a smoking device, as shown and described.

DESCRIPTION

FIG. 1 is a front elevational view of a smoking device, showing my new design;

FIG. 2 is a fragmentary cross-sectional view thereof, taken along line 2—2 of FIG. 1.

The rear and sides which are not shown are identical to the side disclosed in FIG. 1, with the exception of the opening on the front side.
